UNITED STATES PATENT OFFICE.

WALTER I. LEATHERLAND, OF ALEXANDRIA, VIRGINIA.

SANITARY DEVICE.

1,070,618.

Specification of Letters Patent. Patented Aug. 19, 1913.

Application filed March 20, 1913. Serial No. 755,703.

To all whom it may concern:

Be it known that I, WALTER I. LEATHERLAND, a citizen of the United States, residing at Alexandria, Alexandria county, and State 5 of Virginia, have invented and discovered certain new and useful Improvements in Sanitary Devices, of which the following is a specification.

My invention relates to a novel sanitary 10 device, designed to cover closet-seats as a protection against unsanitary conditions and infectious diseases.

The object of said invention is to provide such a protector in a form that may be 15 folded and arranged a considerable number in a single packet of a character readily carried in the pocket, and each device being assembled and folded so as to be conveniently usable.

20 A further object is to provide such a protector of a single sheet of suitable material, such as tissue paper, having tabs formed thereon, and folded so as to be secured in folded form, but readily and quickly opened 25 up for use.

A further object is to provide such a sanitary device, which when folded and arranged in a packet, so presents the finger tabs that they will at all times be easy of 30 access to the user.

In describing my invention in detail, reference will be had to the accompanying drawing, forming a part of this specification, wherein like reference characters de- 35 note corresponding parts in the several views, and in which:

Figure 1, is a view in elevation of a packet of the device arranged for dispensing. Fig. 2, is a view in elevation of a folded device 40 suitable for inserting in the packet or envelop, and Fig. 3 is a plan view of my improved sanitary device.

In the drawings, 1 represents a sheet of thin flexible material, such as any approved 45 grade of toilet paper, having an opening 2, formed therein of substantially the contour of the opening in a closet seat. At the front of the opening is formed a tongue 3, designed to extend down over the front edge 50 of the opening in the seat and protect the user at this point. A finger tab 4 is formed integral with one edge of the device, which when the device is placed in a packet or envelop, will be the top and extend above 55 the front edge of the container as shown in Fig. 1. Said tab 4 provides means for with-

drawing the device from the packet. On another side of the device and adjacent to the tab 4, a second tab 5 is formed which is adapted to fold around the edge of the device when folded and be inserted in a slit 6 in the portion of the device on the opposite side thereof, and thus hold it folded as shown in Fig. 2, for ready insertion in the container or assemblage in packet form. 60 The sheet is also perforated along approximate lines, such as 8, 9, and 10 extending longitudinally and line 7 transversely of the sheet. The perforated lines serve to assist in folding the sheet in the proper form, and 65 also permit it to be readily dissolved to prevent the waste pipes from becoming clogged therewith. Said devices are arranged in an envelop or container 11, having its front edge terminating below the top of the rear 70 wall forming a flap 12, adapted to fold over the front wall, or be inserted under the same in such order that the tab 4 of each sheet can be readily grasped by the finger and thumb 75 and its sheet withdrawn. When the sheets 80 are arranged in the packet form, said tabs 4 extend above the line of the front wall of the container, and are arranged in such manner that the first tab is presented in front of the other and somewhat to the side thereof. In 85 arranging said device for insertion in the envelop they are first folded on line 9, then on lines 8 and 10, then doubled on line 7 so that the slot 6 is brought on the outside fold opposite the tab 5 on the other side fold. 90 Said tab 5 is then folded around the edge and its end inserted through the slot 6, as shown in Fig. 2. The device is then placed 95 in the envelop with the tab piece 4 extending above the front wall of said envelop affording a means whereby the device may be easily withdrawn. After a device is withdrawn from the packet, the user lifts tab 5 out of slit 6 and using said tab as a handle, by a slight quick shake, the device is unfolded and can be placed upon the closet seat 100 without any further manipulation by the user. Said tab is also used to remove the sheet from the seat after using. Thus the device may be readily put up in packet form 105 of six, a dozen or any other desired number in a packet and such packet then sold to users who are enabled to carry them in their pockets or otherwise as most convenient.

Having fully described my invention, what 110 I claim as new and desire to secure by Letters Patent is:—

1. A sanitary protector for use upon closet seats, comprising a sheet of suitable material having an opening, a tongue portion formed on said sheet and adapted to extend down over the front edge of the opening in the seat, a tab formed on one edge of the device and a second tab formed upon another edge and adapted to hold the device in a folded position.
- 10 2. A sanitary device of the class described comprising a sheet of thin flexible material provided with a central opening and with a slot therein on one side and having a tab formed on one edge and a second tab formed on another edge adapted to fold over the edge of the device and be inserted in said slot in the opposite side when the device is folded.
- 15 3. A sanitary toilet device consisting of a sheet of thin flexible material provided with a slot on one outside portion and adapted to be folded and locked in folded position and

having an integral tab formed on the part of the sheet on the other outside portion of the folded sheet and folded over the edge and inserted through said slot, and a tab on the upper edge, all substantially as set forth.

25 4. An article of the class described made of thin material disintegrable by water and adapted to be folded and having weakened 30 lines constituting the folding lines for the sheet and also serving to facilitate the separation and disintegration of the sheet, and means to hold the sheet locked in folded position, substantially as set forth.

35 In witness whereof, I have hereunto set my hand and seal at Washington, D. C. this 19th day of February, A. D. nineteen hundred and thirteen.

WALTER I. LEATHERLAND. [L. S.]
